[57] CLAIM

The ornamental design for a combined ceiling fan and light kit as shown and described.

DESCRIPTION

FIG. 1 is a front perspective view of a combined ceiling fan and light kit incorporating my ornamental design;

FIG. 2 is a rear view of the combined ceiling fan and light kit of FIG. 1;

FIG. 3 is a side view of the representative side of the combined ceiling fan and light kit of FIG. 1, on a reduced scale;

FIG. 4 is a bottom view of the combined ceiling fan and light kit of FIG. 1; and,

FIG. 5 is an enlarged top side view of the combined ceiling fan and light kit of FIG. 1.

The fan blades have been shown broken-away in FIGS. 4 and 5 for ease of illustration.
